United States Patent Office.

WILLIAM SAMUEL COOPER, OF PHILADELPHIA, PENNSYLVANIA, ASSIGNOR
TO COOPER, JONES & CADBURY, OF SAME PLACE.

Design No. 4,780, dated April 11, 1871.

DESIGN FOR HANDLES FOR STOP-COCKS.

The Schedule referred to in these Letters Patent and making part of the same.

I, WILLIAM SAMUEL COOPER, of Philadelphia, county of Philadelphia, State of Pennsylvania, have invented or produced a Design for a Handle for Stop-Cocks, of which the following is a specification.

The figure in the accompanying drawings represents the design for a handle for stop-cocks, *a* being the operating stem of the cock, above which is formed a neck, *b*, and above the latter is a sphere, *d*, terminating at the top in an ornament, *e*.

The projections *f f* from the sphere complete the design.

Claim.

The design for a stop-cock handle, substantially as described and illustrated in and by the accompanying drawings.

In testimony whereof I have signed my name to this specification in the presence of two subscribing witnesses.
